US00D893238S

(12) **United States Design Patent** (10) **Patent No.:** **US D893,238 S**
Bell (45) **Date of Patent:** **** Aug. 18, 2020**

(54) **OVEN BRACKET**(71) Applicant: **Furrion Property Holding Limited**,
Hong Kong (HK)(72) Inventor: **Steven Neill Bell**, Hong Kong (HK)(73) Assignee: **Furrion Property Holding Limited**,
Hong Kong (HK)(***) Term: **15 Years**(21) Appl. No.: **29/694,772**(22) Filed: **Jun. 13, 2019****Related U.S. Application Data**

(63) Continuation of application No. 29/645,800, filed on Apr. 30, 2018, now Pat. No. Des. 851,979.

Primary Examiner — Ricky Pham(74) *Attorney, Agent, or Firm* — Faegre Drinker Biddle & Reath LLP(57) **CLAIM**

The ornamental design for an oven bracket, as shown and described.

DESCRIPTION

FIG. 1 is a front perspective view of an oven bracket illustrating my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is another front perspective view thereof; and,

FIG. 9 is a front perspective view of the oven bracket coupled to an optional oven.

Evenly-sized broken lines illustrate features of the oven bracket that form no part of the claimed design. Long-short broken lines illustrate an optional environment of an oven that forms no part of the claimed design.

1 Claim, 8 Drawing Sheets(56)
